UNITED STATES PATENT OFFICE.

GEORGE P. TILTON, OF ATTLEBORO, MASSACHUSETTS.

DESIGN FOR A SPOON, FORK, OR SIMILAR ARTICLE.

50,825.

Specification for Design.

Patented May 22, 1917.

Application filed March 20, 1917. Serial No. 156,207. Term of patent 14 years.

To all whom it may concern:

Be it known that I, GEORGE P. TILTON, a citizen of the United States, residing in the city of Attleboro, county of Bristol, and State of Massachusetts, have invented a new, original, and ornamental Design for a Spoon, Fork, or Similar Article, which is illustrated in the accompanying drawing, forming part of this application.

Figure 1 in the drawing is a view of the design in front elevation. Fig. 2 is a view

of the same in rear elevation. Fig. 3 is a fragmentary perspective view on the lines A and B of Fig. 1.

I claim—

The ornamental design for a spoon, fork or similar article as shown.

GEORGE P. TILTON.

Witnesses:

PHILIP E. BRADY,
RICHARD F. CRAWFORD.
